UNITED STATES PATENT OFFICE.

JAMES S. MOTTER, OF MILWAUKEE, WISCONSIN, ASSIGNOR TO O'NEIL DURO COMPANY, OF MILWAUKEE, WISCONSIN.

ART OF DECORATING CELLULOID.

Application filed December 23, 1927. Serial No. 242,149.

This invention relates generally to improvements in the art of decorating celluloid and similar material, and particularly relates to the formation of artistic pictures on flexible sheets of transparent material of the 5 pyroxylin or celluloid type.

The main object of the invention is to provide pictures on flexible transparent sheets of material which can be rolled or repeatedly handled without dulling or tearing the 10 picture.

Another object of the invention is to provide colored picture reproductions of a multi-colored product, such as an automobile, in 15 which the colors forming the picture are identical with the colors used on the product.

A further object of the invention is to provide a picture which is practically indestructible and which is adapted for use in 20 catalogues and books subjected to a great deal of handling.

Other objects of the invention will become apparent as the detailed description proceeds.

In the drawings:—

25 Figure 1 is a perspective view of a flexible sheet of celluloid having a picture sprayed thereon in accordance with this invention; and

30 Figure 2 is a cross section, to a greatly enlarged scale, taken on the line 2—2 of Figure 1.

35 As shown in the drawings, the invention comprises a flexible sheet of celluloid 1, having a polished surface 2 and a frosted surface 3. The picture is formed on the frosted surface 2 by spraying the colored lacquers forming the picture through suitable stencils each of which is provided with openings corresponding in outline and location with a particular colored section of the picture.

40 The colors employed in this invention are preferably the nitro-cellulose colored lacquers now in common use for painting automobiles, and each picture is colored to illustrate an automobile in the same colors as are actually applied to the automobile.

In putting this process in practice, the design, in this case, that of an automobile is first laid out on paper in black, white and gray. A halftone is made from this by the usual photographic process, and the design is then printed in the frosted face of the cellu-

loid by any suitable printing process. It is essential that this printing be effected on the frosted face; because the ink tends to squeeze 55 away from the lines and later curl up when the printing is done on the glazed surface.

The various differently colored lacquers are then sprayed through the corresponding apertures in suitable stencils until the colored picture is completed in the same colored lacquers as are used on the automobiles which the pictures are intended to illustrate.

60 The finished picture stands out clearly on the frosted surface alone with the uncolored part of the sheet showing as a translucent background. Preferably, however, I spray the back of the picture and the frosted face 65 of the sheet with a lacquer of neutral tint designed to bring out the best qualities of the 70 colors used in the picture proper.

It is to be understood that many variations in the process described may be used to obtain different effects. The principle involved is that of producing a colored picture design 75 on a sheet of frosted celluloid so that its color combination may be viewed through the celluloid regardless of whether they are applied by hand or in any other suitable manner.

In spraying on the colors on the frosted 80 side of the celluloid the lacquers shrink when drying and slightly bulge the celluloid toward its polished face, thereby giving the picture the effect of being executed in low relief and greatly enhancing the picture from 85 an illustrative point of view.

What I claim is:—

1. The process of decorating celluloid which consists in frosting one face of a sheet of celluloid, transcribing an outline design 90 upon the frosted face of said sheet, filling in the outlined design with appropriate colored opaque lacquers, and coating over the lacquers and frosted face to form a protective backing and background.

2. The process of decorating celluloid which consists in frosting one face only of a sheet of celluloid, transcribing an outline design on the frosted face of said sheet, and filling in the outlined design with appropriate colored lacquers.

In testimony whereof I affix my signature.

JAMES S. MOTTER.
